UNITED STATES PATENT OFFICE

CARROLL M. WILLIAMS, OF SWISSVALE, PENNSYLVANIA

COLLAR BUTTON

Application filed July 7, 1930. Serial No. 466,248.

This invention relates to collar buttons and more particularly to the class of buttons designated shirt studs generally employed for the purpose of attaching collars to the neck band of a shirt.

The collar buttons heretofore known project only through the neck band of the shirt and the collar, the button does not engage the necktie and is therefore fully exposed to view and does not prevent the necktie from sagging. Furthermore the blunt or pointless head offers considerable resistance to the insertion of the collar button in the button holes.

Due to the short axis of the present conventional type of collar button used for the front stud, the center of gravity is near the central portion of the base and in consequence when the collar button is dropped, it not only bounces but generally ends in a long roll to some inaccessible place, where it is certain to be temporarily lost and may even be permanently lost.

An object of this invention is the provision of a collar button having a head designed to serve as a support for the necktie, be easily inserted in the button holes, and prevent rolling of the collar button when it is dropped.

It is also an object of this invention to provide a one piece button of attractive appearance having a head, the shape of which is such that, although the shank of the button is securely retained in the button holes in the ends of the collar while the button is in use, the ends of the collar may be readily engaged and disengaged when necessary without injury to the button holes.

A more specific object of this invention is the provision of a collar button having a specially designed head that will facilitate insertion of the collar button in the button holes with which it is to cooperate and which will also serve as a support for the necktie.

A further object of this invention is to provide a collar button having a base and head connected by a substantially coaxial shank, the head being shaped to prevent the button from rolling or glancing off or "flying" off to some inaccessible place thus to become tem-

porarily lost when dropped on the floor and to facilitate insertion of the button in button holes of the shirtband and collar.

Another object of this invention is to provide an anti-rolling and necktie supporting collar button.

Other objects and advantages will be apparent from a study of the following specification when done in conjunction with the accompanying drawing wherein:

Fig. 1 is a longitudinal sectional view of a preferred embodiment of this invention;

Fig. 2 is a longitudinal sectional view of one type of conventional collar button provided with the requisite structure to embody this invention;

Fig. 3 shows, partly in section, another modification thereof;

Fig. 4 shows the modification shown in Fig. 1 in the position it normally takes when dropped on a support;

Figs. 5 and 6 are front and side views respectively of my invention showing how the necktie is snugly held in the crotch or V of the collar.

Referring more particularly to Figs. 1 and 4 of the drawing, 1 designates a substantially flat circular base of the collar button having the rolled edge 2, which prevents discomfiture to the wearer. The shank 3 having the shape and form of the shank for conventional collar buttons terminates into a rolled spheroidal head 4 which is rolled out into an elongated projection 6, having a length substantially two thirds that of the distance from the base 1 to the head 4. It is, of course, understood that the proportions may be different than here specified. On the inside of the extension a suitable weight 5 is disposed

which has the effect of shifting the center of gravity away from the plane of the base, i. e. away from the central portion of the circular base. The weight may consist of a drop of solder, or any other desirable metal or alloy, while the button proper may be of the kind of materials now known as suitable for such devices. Furthermore, the method of manufacture for this button need be no different than for conventional buttons.

Fig. 2 shows a conventional stud collar but-

ton having a base 11, rolled edge 12, rolled shank 13 and a spherical head 14. Extension 16 is soldered or secured to the head 14 in any suitable manner, the extension being circular in cross section and having a curved tapering contour, as shown, and thus terminating into a point. The point is, however, sufficiently blunt to facilitate handling with safety and comfort. A point having about 10 one eighth the area of the conventional button, has been found to give excellent service.

It will be noted that the head for the collar buttons shown in Figs. 1, 2, and 4 is approximately pear-shaped, the stem end thereof 15 constituting the bluntly pointed end which permits easy insertion of the button into the button holes and holds the necktie in the desired position, giving that neat appearance to the wearer that bespeaks of careful toilet 20 and care of wearing apparel.

The necktie can be moved about in any manner but the knot will remain in proper position. Lowering the chin upon the necktie in any manner such as lowering the jaw or bending the head forward upon the chest does 25 not dislodge the necktie. Furthermore, the invented collar button is invisible from the normal point of view. In this connection attention is called to Figs. 5 and 6, which figures also show how the necktie is supported as above stated.

In Fig. 3 is shown a stud collar button having a circular base 21 provided with a smoothly rolled edge 22, the base having the shape of a section of a hollow sphere. The shank 23 and the head 24 at the junction of the shank and head is of conventional design. The head 24 is provided with a bluntly pointed, elongated, conical projection 26. The collar button and the projection 26 may be of rolled construction, however the projection is hollow, as shown at 27, and is not provided with a weight. The weight 5, shown in Fig. 1, is not essential but may be very desirable 45 for some types of collar button material. A mere inspection of the modifications shown reveals the fact that the collar button embodies a unitary or, as might be termed, integral structure. That is, each part of the 50 button is a single well rounded piece forming a one piece collar button. More particularly, it will be noted, the head and extension thereon are a unitary structure thus providing a collar button that may be manufactured 55 by well known and conventional methods thereby reducing the manufacturing cost per button.

The projection 26 alone or elongated projection 6 alone, is often sufficient to shift the 60 center of gravity of the collar button away from the base, thereby preventing rolling of the button to inaccessible places when the button is dropped. Fig. 4 shows the normal position of the collar button when dropped 65 on the floor. The projection 6 acts as an

anchor. The button, when dropped on a support, will revolve in a circle of approximately two inches.

Since the point of the specially designed button head is relatively small, the button 70 may be readily passed through heavily starched shirt bands and collars.

From the foregoing discussion it is thus obvious that this invention provides a single piece device that acts as a collar button, necktie support and provides a design whereby insertion of the button is facilitated and rolling, when dropped, is very materially reduced, that is, substantially eliminated.

While the foregoing disclosure is directed 80 primarily to three preferred modifications of my invention, it is to be understood that I do not wish to be limited to the specific structural details and dimensional characteristics herein specified, but that other modifications accomplishing the same novel results may be devised falling within the spirit of my invention. I desire that my invention be limited solely by the appended claims.

I claim as my invention:

1. A collar button having a conventional base, a shank of conventional contour terminating into a head having conventional shape at the junction of the shank and head, said head being provided with a weighted 90 bluntly pointed extension whereby handling and inserting of the collar button in the button hole may be accomplished with ease, and whereby rolling of the button when dropped is prevented.

2. A collar button comprising a base the bottom face of the base being in the form of a circular segment of a hollow sphere, a hollow shank of curved contour connecting to the central inner portion of the base and terminating into a unitary hollow semi-spheroidal portion, an elongated, bluntly pointed, hollow extension in line with the axis of the shank unitary with the semi-spheroidal portion, said semi-spheroidal portion and extension forming the head of the collar button.

In testimony whereof I affix my signature.
